UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

PENDANT-SWITCH.

1,170,599.

Specification of Letters Patent.

Patented Feb. 8, 1916.

Application filed November 18, 1910. Serial No. 592,989.

To all whom it may concern:

Be it known that I, REUBEN B. BENJAMIN, a citizen of the United States, residing at Chicago, in the county of Cook and State 5 of Illinois, have invented new and useful Improvements in Pendant-Switches, of which the following is a full, clear, concise, and exact description, reference being had to the accompanying drawing, forming a 10 part of this specification.

My invention pertains to pendant switches, that is to say, to switches of the character which are adapted to be suspended from a pair of flexible conductors.

It is the principal object of my invention to improve upon the existing forms of pendant switch, and to provide one which will be of a simple, durable and efficient construction, which can be readily taken apart 20 for inspection and other purposes, and which can be placed upon the market at a low cost.

A pendant switch constructed in accordance with my invention is described, by way 25 of example, in the following specification, and shown in the accompanying drawings, in which:

Figure 1 is a side elevation of the switch; Fig. 2 is a vertical section taken through 30 the casing, insulating base, and related parts, the major portion of the switch proper, however, being shown in side elevation. The section is taken on the line 2—2 of Fig. 3; Fig. 3 is a vertical sectional view 35 looking at the switch when turned through 90 degrees, the switch members being shown as cut on the broken line 3—3 of Fig. 2; Fig. 4 is a sectional plan, the section being taken on the line 4—4 of Fig. 2; Fig. 5 40 is a view similar to Fig. 4, the section, however, being taken on the line 5—5 of Fig. 3; Fig. 6 is an inverted plan of the switch; Fig. 7 is a perspective view, on a small scale, 45 showing the switch blade and the operating mechanism therefor; Fig. 8 is a horizontal section taken on the line 8—8 of Fig. 3, looking in the direction of the arrows; Fig. 9 is a sectional detail view showing 50 the switch blade operating mechanism, the section being taken on the broken line 9—9 of Fig. 3; Fig. 10 is a horizontal detail view of the switch blade operating mechanism, the section being taken on the line 10—10 of Fig. 2; and Fig. 11 is a perspec-

tive view showing one of the switch contacts 55 and its securing means separated from the remainder of the device.

The pendant switch shown in the accompanying drawings has been constructed by me, and I have found it to be a convenient 60 and efficient device. It is for this reason that I have chosen this device as a good example of an embodiment of my invention. It is to be understood however that the invention may be embodied in different de- 65 vices, and that various portions of the device which I shall hereinafter describe may be used in other connections, without departing from the scope of my invention as defined in the appended claims. 70

In the construction shown in the drawings, 12 designates the upper, and 13 the lower, portion of a two-part cylindrical casing, the parts of which are adapted to be secured together by means of threaded portions 14 and 15 respectively with which the parts are formed. This casing contains an insulating base 16 of cylindrical form, the lower end of which carries the switch mechanism (to be hereinafter described) and the 80 upper end of which is formed with a pair of recesses 17 and 18 respectively through which the conductors by which the switch is suspended are led to binding terminals 19 and 20 which are connected with the contacts which are to be bridged by the switch. The recesses 17 and 18 are disposed so as to form between them a neck 21, the edges 85 of which form shoulders which are adapted to bind against the conductors entering the 90 recesses 17 and 18, as will now be described.

An insulating disk 22 is placed in the part 12 of the casing, above the upper end of the base 16, and is prevented from falling out of the casing, when the parts thereof 95 are separated, by an inwardly extending bead 23 with which the casing part 12 is formed. The disk 22 is provided with a central aperture 24, through which the conductors may pass, in entering the recesses 100 17 and 18. The casing part 12 is formed at its upper end with an open ended conical head 25 containing a pair of insulating gripping members 26. The gripping members 26 are made so as to form, between the upper 105 ends thereof, an elliptical opening having gripping edges 27, between which the conductors, shown in dotted lines in Fig. 2

and designated as 28 and 29 respectively, are securely grasped when the gripping members 26 are forced up into the head 25 by the pressure exerted by the base 16 when the casing parts 12 and 13 are screwed together. Coil springs 30 are inserted between the gripping members 26 and tend to force them apart, so that, when the parts 12 and 13 of the casing are separated and 10 the insulating base removed, and the insulating disk 22 falls upon the bead 23, the gripping members 26 may be separated, by the springs 30, to provide sufficient room between them for the insertion or withdrawal 15 of the conductors 28 and 29.

Supposing that the casing parts 12 and 13 have been separated and the insulating base 16 withdrawn; that the insulating disk 22 is resting upon the bead 23; and that the 20 gripping members 26 have been separated by the springs 30 and are resting upon the disk 22; it will be seen that the conductors 28 and 29 may be inserted easily through the wide space between the gripping members 26 and through the opening 24 of the disk 22, into the recesses 17 and 18 of the base 16. When this has been done, the base 16 may be replaced in the casing, the slack 25 of the conductors 28 and 29 being pulled out through the members 26. Upon the parts 12 and 13 being screwed together, the upper end of the insulating base will press upon the disk 22, and thereby upon the gripping members 26 and will force these 30 members up into the head 25 of the casing part 12. The result of this will be that, owing to the wedge action of the gripping members 26 in the conical head 25, these members will be forced together and the 35 conductors 28 and 29 will therefore be securely gripped between the gripping edges 27 of these members. At the same time the conductors 28 and 29 are separately gripped between the edges of the neck 21, between 40 the recesses 17 and 18, and the edge of the aperture 24 in the disk 22, the aperture 24 being made of a convenient size for this purpose. The conductors are therefore gripped at two points, the double cord made 45 up of the conductors 28 and 29 being gripped between the edges 27 of the members 26, and the separate conductors being gripped between the edges of the neck 21 and the edge of the aperture 24 in the disk 50 22. By this means a very secure holding of the conductors is obtained, since, even if the grip effected by the edges 27 of the members 26, should fail, the conductors will still be secured between the edges of the 55 neck 21 and the edge of the aperture 24 in the disk 22. The danger of strain being imparted to the binding terminals is thus entirely precluded.

The base 16 is formed with a chamber 31 60 opening at the lower end of the base, which

chamber contains the contacts and the operating parts of the switch. Extending vertically along the walls of the chamber 31, at one side thereof are two contact plates 32 and 33 respectively, which are connected 70 with the binding terminals 20 and 19, and are adapted to be bridged by the switch blade to make connection between the conductors 29 and 28. Each of the contact plates 32 and 33 is bent over at its end to 75 form a horizontal lug 34 which is adapted to lie against a shoulder upon the base 16 and to be secured against said shoulder by a screw 35 which passes up through a screw hole formed in the base and enters the particular binding terminal to which the contact plate is connected. By tightening the screws 35, the contact plates 32 and 33, and the corresponding binding terminals 20 and 19, are securely held in position. The lugs 80 34 are provided with upwardly extending ears 36 which enter corresponding recesses 37 formed in the base. These ears define the position of the contact plates and prevent them from swinging about the screws 85 35 when strain is placed upon them by the insertion of the switch blade between them.

A cross bar 37^a is secured against a shoulder formed upon the base 16 by means of a pair of screws 38 extending downwardly 95 through the base and entering the cross bar. Rigidly secured to the cross bar 37^a are a pair of parallel, downwardly extending, legs 39 and 40 which are connected at their ends by means of a pin 41. The switch 100 blade 43 is rockably mounted upon the pin 41; it is formed of a strip of metal bent to form a pair of legs 44 and 45 having holes at their lower end through which the pin 41 passes, these legs being placed close beside the legs 39 and 40 above referred to, and within the same. Between the legs 44 and 45, and also rockably mounted upon the pin 41, is placed a U-shaped member 46 having outwardly extending arms 47 and 110 48, of which the arm 47 is in the form of a segment of a circle and the arm 48 is bent over to form a horizontal stop 49.

The leg 39 is formed at its upper portion with a curved surface 50 upon which 115 is adapted to slide a latch 51 which is pivoted to the leg 45 of the blade 43 and extends through a slot 52 formed in the leg 44 of the switch blade, a tension spring 53 being connected between the latch 51 and 120 the pin 41 to hold the latch normally in engagement with the curved surface 50 of the leg 39, upon one side or the other of a projection 54 which extends upwardly from the curved edge 50. A coil spring 55 is 125 wound upon the pin 41 and has its ends extended upwardly to engage upon either side of the stop 49 (which, it will be remembered, forms part of the U-shaped member 46) and the latch 51 (see Figs. 3, 9 and 10). 130

The effect of the spring 55 will be, therefore, to return the latch 51 into its normal position above the stop 49, after the latch has been moved out of such position, as soon as it is able to do so.

The arm 47 of the U-shaped member 46 is formed, at its upper edge, with a flat surface 56 which is located immediately beneath the latch 51 when the switch blade is in its central position with respect to the U-shaped member 46. If, however, the U-shaped member be rocked about the pin 41, the flat surface 56 of the arm 47 will engage beneath the latch and will gradually lift the same, until the latch is ultimately lifted through a distance sufficient to enable it to clear the projection 54 extending upwardly from the curved surface 50 of the leg 39, whereupon the spring 55, which will have been placed under tension by the rocking of the U-shaped member 46, will cause the switch blade to snap across and enter between the contacts 32 and 33.

In order to enable the rocking movement of the U-shaped member 46 to be effected readily, an operating member, formed of insulating material (such for instance, as vulcanized rubber), is molded thereon. This operating member consists of an insulating block 58 having a pair of lugs 59 and 60 extending laterally therefrom. By pressing upon one of these lugs, the switch blade is moved in one direction, and by pressing upon the other lug, the switch blade is moved in the other direction. If desired, one of the lugs may be provided with an indicating mark, as 61, to show the "on" position of the switch. The lower part 13 of the casing is formed with an aperture permitting the block 58 and lugs 59 and 60 to extend therethrough in a position readily accessible to the hand of a person desiring to use the switch.

The operation of the switch is as follows: Referring particularly to Figs. 2 and 9. Upon pressure being imparted to the knob 59 in an upward direction, the member 46 will be rocked about the pin 41. The switch blade, by reason of the engagement of its latch 51 with the lug 54 of the fixed leg 39, cannot share in this movement and the stop 49 of the member 46 therefore becomes separated, in an angular direction, from the latch 51, the spring 55 being placed under tension. After a portion of the rocking movement of the member 46 has been effected, the cam surface 56 of the arm 47 of the member 46 will strike the lower face of the latch 51 and will begin to lift the latter. By the time the rocking movement of the member 46 has been completed, the latch 51 will have been lifted to a sufficient extent to enable it to clear the projection 54, whereupon the tensed spring 55 will cause the blade 43 to

spring toward the left in Fig. 2, and the right in Fig. 3, to enter between the contact plates 32 and 33 to bridge the latter. When this movement has been completed the parts will be in a position corresponding to that shown in Fig. 9 but with the member 58 tilted in the opposite direction and the latch 51 upon the opposite side of the projection 54 to that shown in Fig. 2. If it is desired to open the switch, pressure is applied to the knob 60, whereupon an operation precisely similar to that described above, but in an opposite direction, occurs.

It will be seen from the above that the switch is absolutely positive in its operation, there being no chance whatever of the blade becoming stuck in a position intermediate its on and off position. Furthermore, the making and breaking of contact by the switch is always effected by a snap action, it being impossible to open the switch, or close it, slowly.

In operating the switch the casing 13 will ordinarily be grasped between two of the fingers and the thumb placed against the central projection of the operating member 58. The operator can tell by the "feel" of the operating member in which direction it must be moved to move the switch blade, and can move it in this direction without shifting the position of the thumb with respect to the operating member.

What I claim as new, and desire to secure by Letters Patent, is:

1. In a snap switch, the combination of a supporting base having a suitable channel therein, a pair of stationary contact members arranged within said channel along the sides thereof, a pair of hangers mounted within said channel, a pivot secured between the free ends of said hangers, a switch blade having a pair of legs pivotally mounted on said pivot, a stop mounted on one of said hangers and arranged beside such switch blade, a latch extending between the two legs of said switch blade and adapted to engage upon either side of said stop, a spring coiled about said pivot between the legs of the blade and having its free ends engaging on opposite sides of said latch, and a rocking lever pivoted on said pivot substantially U-shaped and arranged between the legs of said snap switch, one of the legs of said rocking lever having an in-turned lug mounted between the free ends of said spring and the other leg having a cam portion arranged to engage said latch and lift the same out of engagement with said stop when the lever is rocked.

2. A pendant switch comprising an insulating base, a contact carried thereby, a movable contact for engaging said contact, substantially cylindrical casing means at the lower end of said switch and operating means for said movable contact comprising

an operating member pivoted near the lower end of said switch, said operating member comprising wing portions extending in opposite directions from the pivotal point and 5 movable from a position substantially within said casing to a position extending outside of said casing, and comprising also a central projection between said wing portions extending farther downward than said 10 wing portions.

3. A snap switch comprising a contact, a fixed member having a stop thereon, a pivoted blade adapted to be moved into and out of connection with said contact and having 15 a pair of legs, one of said legs having an opening therethrough, a latch extending between said legs and carried by said blade one end of said latch extending through said opening and adapted to engage upon 20 either side of the stop of said fixed member, a spring for effecting the movement of said blade in both directions, a spring secured at one end to said latch for holding it in latching position; and means for moving 25 said latch out of engagement with the stop

of said fixed member when the first said spring has been set.

4. A switch comprising an insulating base, a contact carried thereby, a movable contact for engaging said contact, casing means 30 for said base and contacts and operating means for said movable contact comprising a rocking member pivoted near a wall of said casing, said rocking member having wing portions extending in opposite directions from the pivotal point and movable from a position substantially within said casing to a position extending outside of 35 said casing and comprising also a central projection between said wing portions extending farther outward than said wing portions.

In witness whereof, I have hereunto subscribed my name in the presence of two witnesses.

REUBEN B. BENJAMIN.
